UNITED STATES PATENT OFFICE.

JOHN H. CLEMENTS, OF COPERAS COVE, TEXAS.

SASH-LOCK.

SPECIFICATION forming part of Letters Patent No. 737,351, dated August 25, 1903.

Application filed February 6, 1903. Serial No. 142,197. (No model.)

To all whom it may concern:

Be it known that I, JOHN HENRY CLEMENTS, of Coperas Cove, in the county of Coryell and State of Texas, have invented a new and useful Improvement in Sash-Locks, of which the following is a specification.

My invention relates to an improvement in devices designed for locking a window-sash at any desired position, its object being to provide a sash-lock that is simple, cheap, and effective in operation.

A further object is to provide a device which may be applied to a window-frame to lock the sash without defacing the frame or sash and one which may be applied to windows already in use.

A further object is to do away with the use of weights to hold the sash at any elevation and provide in their place a device which will be equally as effective.

My invention consists in certain novel features of construction and the particular combination and arrangement of parts, as will be hereinafter fully described, and pointed out in the claim.

In the drawings, Figure 1 is a perspective view showing my improvement in use. Fig. 2 is a vertical longitudinal view of the same. Fig. 3 is a detached perspective view of the 30 guide-rod. Fig. 4 is an inverted perspective view of the apertured plate. Fig. 5 is a detached detail perspective view of the clutch-loop. Fig. 6 is a perspective view of a slightly-different form of guide-rod.

A represents a window-frame of the usual construction, but without weight-boxes and pulleys, as they are rendered unnecessary by the use of my device. The usual guide-beads are used, between which the sashes are adapted 40 to slide.

To the lower sash, preferably its lower right-hand corner, is secured the plate B, provided with the square aperture or opening B' and the flanges B² B³, surrounding said opening on the outer face of said plate. The rear face of the plate B is provided with the curved sockets b b at the sides of the horizontal center of the opening B'. A clutch-loop or yoke C, which is oblong both vertically and horizontally and has 45 a rearwardly-extending neck c, from which at its rear end project from each side horizon-

tally the pivots or trunnions c' c', is passed through the opening in the plate B from the rear, the pivots fitting in the sockets b b thereof. The opening through the yoke or clutch-loop C is oblong and fits on the rod E, secured to the window-casing, as shown, the cross-section of said rod being also oblong. Said rod is perfectly straight throughout nearly its entire length, but near each end it is provided with 55 bends e e, one of which may be angular, but the other one must be curved to permit the passing of the clutch-loop over it onto the main portion of the rod. If desired, both ends may be curved. The bends terminate in extensions or feet e² e², having openings to receive screws by means of which the rod is secured to the frame. The inner edges of flanges B³ are slightly beveled to allow free movement of the clutch-loop or yoke. The 60 oblong opening through the clutch-loop or yoke C is slightly larger than the perimeter of the rod E, so that when said clutch-loop is in a perfectly horizontal position it will slide freely up and down on said rod.

The various parts of the device having been properly assembled, to operate the sash it is simply necessary to grasp the knob or handle h, secured to the center of the lower rail of the lower sash with one hand and the clutch-loop C with the other, holding the said loop horizontal, and raise both together, whereupon the clutch-loop will slide freely upon the rod E until the sash has been raised to its desired height, when the hold on the knob 75 h and clutch-loop C is released. The weight of the sash will then be thrown on the clutch-loop and it will rock on its pivots c' c' by reason of the opening through the plate being larger than the height of the loop C, throwing it out of its horizontal position and cause two of the inner walls of the opening through the clutch-loop to bind against the rod E on opposite sides, the rear wall of the opening binding at its lower edge and the front wall binding against the rod at its upper edge, and thus securely clamp or lock the sash against downward movement. When it is desired to lower the sash again, the clutch-loop is brought to its horizontal position again by one 80 hand and the sash lowered by the other hand pressing downwardly on knob or handle h.

The various parts may be made of cast steel, iron, or other suitable metal and ornamented as desired.

Having thus described my invention, what 5 I claim as new, and desire to secure by Letters Patent, is—

The combination with a window frame and sash, of a rectangular rod secured to the frame by curved bends at the ends, a rectangularly-apertured plate secured to the sash having curved sockets in its rear face, horizontal and vertical flanges surrounding the aperture on the outer face of the plate, the inner walls of the horizontal flanges being beveled, a clutch-loop of less area than the aperture in the plate having a rectangular central aperture,

20 said clutch-loop passed through the apertured plate from the rear, and circular pivots or trunnions projecting horizontally from each side of the loop at its rear end and adapted to fit and rock in the sockets in the rear face of the apertured plate, whereby said clutch-loop will be adapted to slide on the rectangular rod, when held in a horizontal position and to rock on its pivots and bind on opposite 25 faces of the rod by downward pressure of the sash to lock said sash at any desired height.

JOHN H. CLEMENTS.
